(57) **CLAIM**

The ornamental design for a squirrel carousel feeder, as shown and described.

DESCRIPTION

FIG. 1 is an exploded top front left perspective view of a squirrel carousel feeder showing my new design; FIG. 2 is an exploded top front right perspective view thereof; FIG. 3 is an exploded bottom rear left perspective view thereof; FIG. 4 is an exploded bottom rear right perspective view thereof; FIG. 5 is an exploded front elevational view thereof; FIG. 6 is an exploded rear elevational view thereof; FIG. 7 is an exploded left elevational view thereof; FIG. 8 is an exploded right elevational view thereof; FIG. 9 is an exploded top plan view thereof; FIG. 10 is an exploded bottom plan view thereof; FIG. 11 is an enlarged top front left perspective view thereof; FIG. 12 is an enlarged bottom rear right perspective view thereof; FIG. 13 is an enlarged front elevational view thereof; FIG. 14 is an enlarged rear elevational view thereof; FIG. 15 is an enlarged left elevational view thereof; FIG. 16 is an enlarged right elevational view thereof; FIG. 17 is an enlarged top plan view thereof; and, FIG. 18 is an enlarged bottom plan view thereof. The broken lines illustrate portions of the squirrel carousel feeder that form no part of the claimed design.
